UNITED STATES PATENT OFFICE.

EDMUND B. KIRBY, OF ST. LOUIS, MISSOURI.

PROCESS OF OPERATING ORE-CONCENTRATING TABLES.

1,105,799.

Specification of Letters Patent.

Patented Aug. 4, 1914.

Application filed July 1, 1910. Serial No. 569,945.

To all whom it may concern:

Be it known that I, EDMUND B. KIRBY, a citizen of the United States, residing at St. Louis, in the State of Missouri, have invented a certain new and useful Improvement in Processes of Operating Ore-Concentrating Tables, of which the following is a full, clear, and exact description.

This invention is a new method of concentrating pulverized ore by the use of a well known form of concentrating tables, and of recovering the valuable constituents of such ore. In other words, it is a new method of concentrating and recovering the valuable constituents of ore with the assistance of well known concentrating tables.

In the regular and usual operation of concentrating tables, of which there are many varieties (the well known Wilfley table being an example) the differential vibration of the table in one direction, and the flow of water across the table in a relatively transverse direction, cause the grading of the pulverized ore thereon, and the arrangement of the various grades in bands of which the front band includes the heaviest and most valuable mineral constituent of the ore. These bands extend and slowly move in a generally diagonal direction, which is the resultant of the two forces (viz. the differential vibration of the table and the force of the water) which cause such arrangement and flow. It has long been a matter of common knowledge that these bands of the different grades of the ore overlap each other,—the rear edge of each band being overlapped more or less by the front edge of the next band behind it. It has also long been known that the lapping parts of these bands are imperfectly graded. These conditions and the attendant disadvantages and resulting losses, have, however, heretofore been assumed to be the incurable results of the operation of such tables. In association with the concentrating tables, means have heretofore been employed to split the bands for the purpose of recovering separately the different grades which have been formed and arranged as stated. Sometimes several grades are recovered, but heretofore either with loss, or else the grades are not entirely separated from each other. Sometimes it is only the heavy mineral in the front band that is to be recovered. For the purpose of comparing the invention which this patent covers with the prior practice, it may be as-

sumed that it is only the front band which contains valuable mineral which it is desired to recover. The band splitting means heretofore employed have generally been in the form of some kind of adjustable dividing edge such as a blade adjustable on the table, at the delivery end thereof; and this blade has been placed so as to cut off and segregate the whole or some part of the front band as the material passes off the table. The most general practice is to place said splitting device so that, as nearly as possible, it will split the front band along the surface line or division between it and the next band. To the extent which this can be done, practically, the material which is split off and recovered is very nearly pure, but obviously there is lost all of the material of the front band which is overlapped by the next band, or which is imperfectly separated from the material of the next band. Of course, if one desired to recover all of the valuable mineral belonging in the front band, the splitting off blade could be adjusted so that, as nearly as possible, it will split the front band in the line of the rear edge of the underlapping part thereof. This very clearly would recover nearly all the valuable material belonging to the front band, but mixed with it will be all of the less valuable material which overlaps and is partly blended with the rear part of the front band. Again, one may compromise between these two positions, and seek to split the band somewhat intermediate of the rear edge of the front band and the front edge of the next band. But in any event, the separation of the bands is, as stated, effected at or near the delivery end of the table. None of these adjustments are ideal; and whether the one or the other adjustment be attempted will depend upon circumstances, although, generally speaking, the first adjustment referred to is that which is most commonly sought for. None of these adjustments can, however, be accurately maintained in practice, because the bands actually fluctuate back and forth on the table, so that, if the splitting device be accurately adjusted for the then existing conditions to secure whatever result is desired, the positions of the bands might, and generally do, in the next few minutes, so change that these desired results would not be secured. Any variation in the force or volume of the water used, or any variation in the force of the

jerk of the table, and some other causes which are known and need not be specified, produce always, in practice, these small fluctuations of the moving bands forward and backward upon the table top. My method of operation, however, is such that small fluctuations of the band do not much affect its successful operation, nor prevent the recovery of substantially all of the valuable mineral in the front band; in substantial purity.

My method consists in splitting off and removing the front edge of the front band—any part of it, back to the surface line of division between it and the next band—before the moving bands reach the end of the table, so that what remains will be subjected to the combined influence of the differential vibration and the water flowing across the table. The material so split off and removed had, before its removal, served as a barrier which prevented the wash water from acting upon and grading the lapping parts of the two bands and these shielded parts are now exposed to the action of the wash water, with the result that very soon the greater part of these overlapping strata are graded and a new front band of the heavy valuable mineral created. It may be that some part of the rear edge of this newly formed front band is overlapped by the next band. If this is so, and if the quantity so overlapped makes it desirable, the front part of this newly formed band may be again split off and removed, and such of the material as remains again be subjected to the influence of the water and the jerking of the table. In fact, these operations may be repeated as often as desired. They may even be repeated enough times to recover in substantial purity two or more grades of mineral, if there be more than one band of material which it is desired to recover; for after the material originally in the front band is all recovered, the next band may be treated in the same way, before the end of the table is reached. In any event, whether the front edge of the front band be cut off more than once for regrading, a very large part of the high grade mineral which was at first overlapped by or mixed with the material properly belonging in the next band will be saved and recovered in substantial purity; and the described operations may be repeated until the high grade material which remains is an inconsiderable fraction of the whole.

It is obvious that small fluctuations of the bands back and forth on the table do not necessarily interfere with the successful operation of the process. The cutting off means may be placed so that the fluctuation of the bands will only result in increasing or decreasing the width of the strip of pure

mineral which is removed. This may or 65 may not vary the fraction of this high grade ore which is finally recovered; but in any event, the unrecovered fraction will always be small, and the percentage of pure high grade mineral recovered will be very large, 70 by comparison with the results obtained by the methods of operating concentrating tables heretofore practised.

In the drawing Figure 1 is a plan view showing, more or less conventionally, a concentrating table adapted for the purpose of this invention. The means for vibrating the table are not shown, nor are the means for discharging the wash water onto the table. These means, however, are well known in 80 the art and are essentially well known features of practical concentrating tables, and it is to be understood that whatever variety of concentrating table be employed, they should be provided with these invariably 85 present parts. Fig. 2 is a sectional view on the plane of line F—G on Fig. 1. Fig. 3 is a sectional view on the plane of line H—I on Fig. 1; and Fig. 4 is a sectional view on the plane of line J—K on Fig. 1. 90

Referring to the parts by reference letters, A represents the concentrating table which is slightly inclined downward from front to rear, and *a*, *a'* represent slots through the table. *b* represents the front band of the heavy mineral constituents of the ore, and *c* represents the band of the next grade, which we may call the middlings, and *d* represents what may be called the tailings. These bands, as they appear at 100 the left end of said Fig. 2 are, as they are originally formed, the overlap of the rear edge of the front band by the next band behind it being clearly shown. This slot *a* is so placed that a greater or less part of 105 the front band *b* will pass over it and will drop through it, these slots being a convenient method of splitting off and removing the front edge of the front band. The remainder of the materials pass behind this 110 slot and flow toward the delivery end of the table in the diagonal direction shown, and the uncovered front part of the material is subjected to the action of the wash water, whereby it will be regraded and rebanded. 115 That is to say, a new front band *b'* of the heavy mineral will be formed. The slot *a'* is so placed that more or less of the unlapped part of this new front band *b'* will pass over it and will drop through it. The material 120 which passes behind the slot is again subjected to the washing and grading action of the water, whereby a new front band *b²* is formed; and this may be recovered at the end of the table. As will be seen from Figs. 125 2, 3 and 4, the overlapped part of the front band grows progressively smaller, and, at the delivery end of the table is so small as to

include only a very inconsiderable fraction of all of the high grade mineral which the pulverized ore originally contained.

Having thus described my invention, what

5 I claim is:

1. The herein described process of concentrating ores which consists in delivering the ore in a pulverized condition onto a concentrating table, in imparting to said table 10 a differential vibration, and in simultaneously discharging a forceful sheet of wash water crosswise of the table in a direction transverse to the direction of the vibration, whereby said pulverized ore is arranged in 15 bands and caused to travel along the table in a direction which is the resultant of the two stated forces, in removing the front portion of the front band of material at such a distance back from the discharge end of 20 the table that the remaining material before it reaches said discharge end will be rebanded by the combined action of said wash water and differential vibration.

2. The herein described process of concentrating ores which consists in delivering the ore in a pulverized condition onto a concentrating table, in imparting to said table a differential vibration, and in simultaneously discharging a forceful sheet of wash water crosswise of the table in a direction transverse to the direction of the vibration, whereby said pulverized ore is arranged in bands and caused to travel across the table 30 in a direction which is the resultant of the two stated forces, in removing the front portion of the front band of material at such a distance back from the discharge end of the table that the remaining material will be re-

banded before it reaches said discharge end 40 by the combined action of said wash water and differential vibration, and in repeating as often as may be required, this removal of the front part of the front band, and subsequent subjection of the material to the combined action of the differential vibration of the table and the forceful sheet of wash water for a long enough time to effect a rebanding of said material.

3. The herein described process of recovering clean values from pulverized ore with the assistance of a concentrating table whereon the wet ore is caused to arrange itself in diagonally disposed overlapping bands by the combined action of (1) the differential 55 lengthwise vibration of the table, and (2) a forceful sheet of wash water which flows transversely across said table, and is caused to travel along said table toward the discharge edge thereof in a direction which is 60 a result of the two stated forces,—said process consisting in removing a large part of the non-overlapping front edge of the front band of said ore at a point on the table such 65 that the remaining ore will be rebanded before it reaches the discharge edge of said table, and in subsequently segregating from the rebanded ore a greater part of the non-overlapping front edge of the newly formed front band.

In testimony whereof, I hereunto affix my signature in the presence of two witnesses.

EDMUND B. KIRBY.
